UNITED STATES PATENT OFFICE.

THOMAS W. SLUTZ, OF CROWLEY, LOUISIANA.

PNEUMATIC STACKER.

SPECIFICATION forming part of Letters Patent No. 718,395, dated January 13, 1903.

Application filed April 11, 1902. Serial No. 102,341. (No model.)

To all whom it may concern:

Be it known that I, THOMAS W. SLUTZ, a citizen of the United States, residing at Crowley, in the parish of Acadia and State of Louisiana, have invented certain new and useful Improvements in Pneumatic Stackers, of which the following is a specification.

In that class of pneumatic straw-stackers in which the straw is fed into the conveyer-chute in advance of the fan in such manner that the straw does not pass through the fan difficulty has heretofore been experienced in preventing the straw from being blown backward through the inlet; and the object of my present invention is to produce a structure by means of which the straw can be positively fed into the discharge-chute at a point in advance of the blast-fan and in such manner that by no means can the straw be forced backward through the inlet so as to become choked therein.

The accompanying drawings illustrate my invention.

Figure 1 is a vertical section of my improvement in connection with a separator of usual form. Fig. 2 is a plan section on line 22 of Fig. 1; and Fig. 3 is a sectional detail, on an enlarged scale, of the essential elements of my invention.

In the drawings, 5 indicates a separator-casing of any desired and well-known form, in which are mounted the straw-separating rake-bars 6 and the grain-cleaning screens 7. Communicating with the casing 5, one at each side thereof, are two fan-casings 8, each of which is provided with a discharge-spout 9. The two discharge-spouts are led upwardly and inwardly, so as to be brought together into a single discharge-tube 10, which leads upwardly to the single stacker-tube 11. The two fans 8 are of such size as to create the necessary blast through tubes 10 and 11, and the eye of each of said fans communicates with the interior of casing 5, so as to receive the chaff from the screen 7, the said chaff therefore passing through the fans and being easily distributed to the two fans by means of inclined vertically-arranged deflectors 12, which, if desired, may be hinged at 13, so as to be swung out of the way. Formed in the upper side of tube 10, preferably at about the point of junction of the two tubes 9, is an opening 14, to-

ward which leads a hopper 15, the upper end of said hopper lying in position to receive the straw from the rear ends of the rake-bars 6. Located adjacent the upper or forward edge of opening 14 is a feed-roller 16, which is held in stationary bearings and is adapted to be driven in the direction indicated by the arrow by means of suitable pulleys and belts connecting the shaft thereof with a driven portion of the machine. Supported in suitable hangers 17 from the shaft of roller 16 is a coacting roller 18, which is movable toward and from roller 16, but is yieldingly normally held close to roller 16 by means of suitable springs 19, one of which is shown in dotted lines in Fig. 3. The periphery of roller 18 lies close to that wall of tube 10 which forms the lower or rear edge of opening 14. The opening 14 at its forward side may be continued to the point a, or thereabout, if desired, the periphery of roller 16 fitting close thereto; but I prefer to form the forward edge of opening 14 by a lip 20, which follows the curvature of roller 16 and lies close thereto, extending toward the mouth between the two rollers 16 and 18, as clearly shown in Fig. 3. By this means all possibility of the creation of a current of air between the lip 20 and roller 16 by reason of the blast through tube 10 in the direction indicated by the arrow is prevented. In operation, therefore, the straw passes from the rake-bars 6 in the hopper 15 and is engaged by the two rollers 16 and 18 and fed positively therebetween into tube 10 at right angles to the direction of blast, the rollers preferably rotating at a considerable speed, so as to project the straw into the tube with considerable force. As a consequence the forward ends of the straws will be positively forced by the point of conjunction between rollers 16 and the wall of tube 10, so as to prevent the possibility of any straw lodging in said joint, and thus preventing any choking of straw at the entrance.

I claim as my invention—

1. In a pneumatic stacker, the combination with a fan, and a discharge-spout leading therefrom the said discharge-spout having an opening formed therein in advance of the fan, of a pair of feed-rollers arranged outside of the spout immediately adjacent the oppo-

site edges of the opening, and means for driving one of said feed-rollers, whereby the straw may be projected into the discharge-spout past the forward edge of the opening 5 so as to prevent the blast passing through the discharge-spout from the fan from forcing the ends of the straw between the forward feed-roller and the wall of the spout.

2. In a pneumatic stacker, the combination 10 with a fan, and a discharge-spout leading therefrom and having an opening 14 formed thereinto, a curved lip 20 forming the for-

ward edge of said opening, of a pair of feed-rollers 16 and 18 arranged adjacent said opening, the lip 20 extending up toward the point 15 of coaction of the rollers, substantially as and for the purpose set forth.

In witness whereof I have hereunto set my hand and seal, at Indianapolis, Indiana, this 2d day of April, A. D. 1902.

THOMAS W. SLUTZ. [L. S.]
